UNITED STATES PATENT OFFICE.

PAUL SCHWERIN, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed December 15, 1923. Serial No. 680,813.

This invention relates to electron discharge devices, and more particularly to vacuum tubes, an object being to utilize a unitary means such as an insulating block, 5 both as an electrode support and an electrode spacing means.

A further object is to so shape and dimension an insulating block that it may be used for the above and similar purposes 10 and may be formed of porcelain or an equivalent material by molding. Porcelain is a desirable material because of its highly refractory nature, low vapor tension and high insulating qualities. When the block 15 is constructed as described herein, porcelain is also a very inexpensive material, since 15 all of the forming operations are accomplished by molding.

In accordance with the invention, an apertured insulating block with wedge-shaped projections on opposite ends is provided, the block serving to align a pair of parallel plate electrode surfaces which support the block. The block also serves to support a 25 filament in proper space relation to the plates. A plurality of wires are attached to the plates and looped over the wedge-shaped projections and crimped adjacent the apices of the wedge-shaped projections. 30 This construction provides an efficient structure whereby the electrodes are maintained in their proper space relation so that uniform results are obtained when the device is operated.

Referring to the drawings, Fig. 1 is a perspective view of an electron discharge device with a part broken away to clearly illustrate the invention. Fig. 2 is an elevation of the insulating block.

Referring now to Fig. 1, an electron discharge device is illustrated, which consists of a glass enclosing vessel 10 having a re-entrant stem 11. Encircling the stem 11 is a corrugated metal collar 12, the corrugations serving to hold the collar 12 on the stem 11 wholly by friction. Integral with the collar 12 is a ribbed supporting member 13, which carries the corrugated anode plate 14. Parallel to plate 14 is another corrugated plate 14 which is supported from the collar 12 by a supporting member not shown, corresponding to supporting member 13. An insulating block 15, which may consist of porcelain, is provided with an elongated

concentric aperture 16. Projecting from 55 either end of the insulating block 15 are polyhedral projections 17. The projections 17 are formed integral with the apertured portion 15 and are provided with inwardly extending portions 18, below the 60 lower plane of insulating block 15. The width of the polyhedral projections 17 depends upon the spacing required between the corrugated plates 14 and may be changed to meet various conditions. 65

In the assembly of the electron discharge device, the insulating block 15 is placed on the upper edges of the corrugated plates 14, with the projections 17 and extensions 18 being inserted between the plates 14. 70

A plurality of wires 19 are fastened to the upper ends of the plates on the exterior surfaces thereof, by any desirable means, preferably by spot welding. The wires 19 form loops over the projections 17, which 75 are then crimped at 20 with a crimping tool. This arrangement securely holds the insulating block to the plates and draws the plates against the lateral sides of the projections 17. 80

The filament hooks 21 may be fastened to the upper surface of insulating block 15 at diagonally opposite points 22. These hooks are then bent so that their shanks project within the elongated concentric aperture 16. 85 The shanks of the filament hooks 20 are positioned in the aperture so that their free ends lie between and are in a line parallel to the plates 14. A filament 23 is positioned between the plates 14 and supported at the 90 upper end by the hooks 21 and at the lower end is held by springs 24, only one of which is shown.

Although the invention has been described with respect to a two-electrode vacuum tube, 95 it is apparent to those skilled in the art, that this arrangement can be applied to other types of vacuum tubes. Furthermore, it is to be understood that this invention is not limited to the use of porcelain as an 100 insulating block, since other forms of insulating material can be used.

What is claimed is:

1. An electron discharge device, comprising a pair of plates, an apertured insulating block, integral wedge-shaped terminations on said block, said wedge-shaped terminations extending between said plates and

connections on said plates, said connections being crimped at the apex of said wedge-shaped terminations.

2. An electron discharge device, comprising a plurality of plates, an insulating block resting on and extending over the edges of said plates, integral terminations on said block, said terminations being substantially positioned between said plates, and connections on said plates, said connections being crimped adjacent the top of said terminations.

3. An electron discharge device, comprising a pair of parallel plates, an insulating block, wedge-shaped projections on said insulating block having parallel surfaces, one end of each of said plates being adjacent said surfaces, and wire loops attached to said plates, said loops being indented above said projections.

In witness whereof, I hereunto subscribe my name this 11 day of December A. D., 1923.

PAUL SCHWERIN.
